PORTABLE PIPE CLEANING DEVICE

Aaron J. Levine, Chicago, Ill.

Application February 14, 1955, Serial No. 488,084

3 Claims. (Cl. 15—104.3)

This invention relates to portable pipe cleaning device for cleaning drains and has for its principal object the provision of a new and improved device of this kind.

It is a main object of the invention to provide an improved portable tool for rotating and simultaneously feeding longitudinally a flexible sewer rod for cleaning drains.

Another object of the invention is to provide a unitary device for housing and driving a long flexible sewer rod, from which device the rod is payed out as needed.

Another object of the invention is to provide a high quality device of this kind that can be manufactured at a cost low enough to render the device available to owners of small buildings such as homes, motels, and apartment buildings.

Another object of the invention is to provide a sewer rod that is simple to adjust and operate, thereby to enable a handy man to clean out a plugged drain without having to call a plumber.

Further objects of the invention not specifically mentioned here will be apparent from the detailed description and claims which follow, reference being had to the accompanying drawings in which a preferred embodiment of the invention is shown by way of example and in which:

Fig. 1 is a perspective view of the invention;

Fig. 2 is a fragmentary plan view;

Fig. 3 is a cross sectional view, taken substantially along the line 3—3 of Fig. 2, looking in the direction of the arrows; and

Fig. 4 is a cross sectional view of the frame taken along the line 4—4 of Fig. 3, looking in the direction of the arrows.

Flexible sewer rods consisting of a tightly coiled steel wire, carrying at its forward end a cutting element, are commonly used to clear blocking obstructions from drainpipes leading from sinks, lavatories, and the like. Such devices are worked through the pipe by rotating the sewer rods and in the prior art of which I am aware are numerous devices for accomplishing this purpose.

Sewer rods of this type are provided in lengths of fifteen (15) feet and upwards and generally frusto-conical casings have been provided to encase the rod in coiled condition. In certain instances the casing has been rotatably mounted upon a base adapted to rest upon the floor and the rod has been run through a propelling unit by which it is rotated and payed out of the casing as required in operation in the drain. In other instances, the casing has been supported upon a suitable handle and the sewer rod rotated by rotating the casing around the axis of the rod as a center.

The present invention improves upon these former devices by providing a self-contained unit consisting of a framework in which a tubular shaft is journaled. A casing is supported upon this shaft to enclose the portion of the sewer rod not being used. A collar on the shaft contains a set screw threaded through the collar and the shaft into engagement with the rod to secure the rod with respect to the tubular shaft. A bevel gear fixed upon

2

the shaft is meshed with a bevel gear fixed upon the framework and a crank provided to rotate the latter bevel gear, thereby to rotate the shaft, sewer rod and casing as required.

- 5 A pistol grip handle extends downwardly from the shaft and is located near the center of gravity of the device so that the device may be conveniently supported in one hand while the other hand is employed to rotate the rod as required to clear the drain.
- 10 In order to permit manufacture of the device at a price low enough to render it available for use in homes, motels and small apartment buildings, the handle is cast, preferably die cast, in such a manner as to require a minimum of machining in the fabrication of the device.
- 15 As will be seen in the drawings, the device of the present invention consists of a base unit 10 containing at its opposite ends semi-cylindrical bosses 11 which face in the same direction. The base 10 also contains a centrally located semi-cylindrical boss 12 which faces in the direction opposite to the facing of the bosses 11. Bosses 11 and 12 thus form journals by which a tubular shaft 13 is supported in the device.
- 20 Mounted upon one end of the tubular shaft 13 by a hub 14 is a generally frusto-conical casing 15 in which 25 the flexible sewer rod 16 is coiled, this rod extending through the hub 14 and tubular shaft 13 and therebeyond as needed. The projecting end of the rod 16 carries a cutting tool, not shown since it forms no part of the present invention.
- 30 A collar 17 encircles the shaft 13 and carries a set screw 18 that is threaded through the collar and shaft into engagement with the rod 16 to lock that rod with respect to the shaft. A suitable handle 19 is provided to facilitate operation of the set screw 18.
- 35 Fixed upon the shaft 13 is a bevel gear 20, and mounted upon the framework is a second bevel gear 21 secured thereon in convenient manner, such as by a stud screw 22 threaded into a portion 23 of the boss 12. A crank 24 is fixed upon the bevel gear 21 to permit an operation of 40 the crank to rotate the gears and shaft 13, the casing 15, and the sewer rod 16.
- 45 The framework 10 also carries housing members 25 and 26 by which the gears 20 and 21 are partly encased and protected.
- 50 Depending below the framework 10, with its axis at right angles to the axis of shaft 13, is a pistol grip handle 26 which is located substantially in alignment with the central boss 12 of the framework and near the center of gravity of the device when a substantial portion of the rod 16 is coiled within the casing 15.
- 55 In operation of the device, the set screw 18 is loosened and sewer rod 16 payed out of the device and fed into the drainpipe as far as it will go. The set screw 18 is then tightened and crank 24 is operated to rotate the sewer rod and pressure longitudinally of the rod is simultaneously applied through the handle 26. When the rod has thus been advanced as far as possible, set screw 18 is loosened and more rod payed out, the process continuing until the obstructions in the drainpipe are encountered and reamed out by the cutting head on the forward end of the sewer rod.
- 60 The construction as shown lends itself to the fabrication of a high quality serviceable tool that can be marketed at a price low enough to make it attractive to home owners and the like, who are thereby enabled to clear plugged drains themselves without having to go to the expense of calling in a plumber. The arrangement of opposed semi-cylindrical surfaces in bosses permits casting the journals by which the shaft is journaled in the device and eliminates the necessity of machining the bearing surfaces, 65 obviously reducing the cost of fabricating the device.
- 70 While I have chosen to illustrate my invention by

showing and describing a preferred embodiment of it, I have done so by way of example as there are many modifications and adaptations which can be made by one skilled in the art within the teachings of the invention.

Having thus complied with the statutes and shown and described a preferred embodiment of my invention, what I consider new and desire to have protected by Letters Patent is pointed out in the appended claims.

I claim:

1. A hand held and operated device for cleaning drains comprising a tubular shaft; a frusto-conical container having a hub fixed on one end of said shaft; a flexible rod coiled within said container and projecting through said shaft; a frame; a pair of semi-cylindrical bosses at opposite ends of said frame, one of which abuts said hub; a 15 third semi-cylindrical boss on said frame between and disposed oppositely of said pair of bosses, said bosses together journaling said shaft in the frame; a bevel gear fixed on said shaft adjacent said third boss; a second bevel gear journaled on said frame and meshed with said first bevel gear; a crank fixed on said second bevel gear rotatable to rotate said shaft, container and rod; a collar on said shaft abutting the other one of said pair of bosses; 20

and a set screw threaded through said collar and said shaft into engagement with the rod to fix the rod longitudinally with respect to the shaft.

2. A device as specified in claim 1, in which the frame is T-shaped with the pair of bosses at opposite ends of the top portion and a pistol grip depends from the top portion substantially in alignment with said third boss.

3. A device as specified in claim 1, in which the frame is a single piece casting and includes a housing partially encasing said first bevel gear.
